UNITED STATES PATENT OFFICE.

FELIX E. LIETZ, OF BUFFALO, NEW YORK, ASSIGNOR TO THE FLINTKOTE COMPANY, OF BOSTON, MASSACHUSETTS, A CORPORATION OF MASSACHUSETTS.

SHINGLE LOCK.

Application filed May 7, 1927. Serial No. 189,564.

This invention relates to a lock or fastener for flexible shingles and more particularly a locking device for a shingle having a slot in its turned-under corner such, for example, as covered by Letters Patent of the United States #1,583,254 granted to me May 4, 1926.

The object of the invention is the provision of an inexpensive compensating fastener which permits the shingle to be readily adjusted sidewise as well as up or down to aline it properly with adjacent shingles and at the same time allow the shingle to expand or contract both vertically and laterally, in response to changes of temperature, thus preventing buckling of the shingle and permitting it to lie smooth under all weather conditions.

In the accompanying drawings Figure 1 is a fragmentary top plan view of a roof embodying the invention. Figure 2 is a similar enlarged view, partly in section, the sectional portion being on line 2—2, Figure 4. Figure 3 is a view similar to Figure 2, showing the lateral shifting capacity of the fastener. Figure 4 is an enlarged vertical section on line 4—4, Figure 1. Figure 5 is a perspective view of the fastener.

Similar characters of reference indicate corresponding parts throughout the several views.

10 indicates the usual sheathing or roof boards and 11 the starting strip of roofing material laid along the lower margin of the roof.

The shingles 12 are preferably constructed of composition roofing, such as felt saturated with asphalt and faced with crushed slate or similar mineral; and they are cut 40 square and laid diagonally in overlying courses as usual.

The lower corner 13 of each shingle is folded under its body and provided centrally with a vertical slot 14 which interlocks with the improved fastener.

This device, in the preferred form shown in the drawing, comprises a pointed shank 15 adapted to be driven into the roof, a cranklike arm 16 projecting from its outer end and a head 17 of substantially T-form, whose stem is parallel with the shank or nearly so. These several parts can be cheaply formed from a single piece of round steel

wire, but the fastener may be cast or stamped if desired. The cross-head of the fastener is long enough to overlap the turned undercorner of the shingle some distance on either side of its slot to form a strong lock which firmly holds that corner down in place against the lifting action of wind storms.

In laying and locking a shingle with this fastener, assuming a course of shingles to have been previously laid, the shank 15 of the fastener is driven through the upper corner of an underlying shingle into the roof boards at a point below and in line with the meeting side corners of two previously laid shingles and with the crank arm 16 extending above the shank, as shown by full lines in the drawing. A shingle with its slotted corner turned under, is then interlocked with the cross bar of the T-head by bringing the slot in line therewith, as shown by dot and dash lines Figure 2; then giving the shingle an upward quarter turn to its normal position, as shown by broken lines in said figure bringing the slot at right angles to the cross head and finally nailing the side corners of the shingle to the roof boards.

By the use of this fastener, the slotted shingle after being interlocked with the driven fastener and before being nailed at its side corners, can be shifted not only up or down to accurately aline its folded lower edge and side corners with those of adjacent shingles in the same course, but it can also be shifted sidewise, the crank arm 16 of the shank following such lateral movement of the shingle as shown by dot and dash lines Figure 3, and turning the shank in its opening, without however, loosening the fastener and rendering it less secure. By this capacity of the locking head of the fastener to move or swing laterally more or less after the shingle has been interlocked therewith, the fastener compensates for lateral expansion and contraction of the shingle, thus effectively guarding against its buckling, keeping it flat and smooth and preserving the sightliness of a roof covered with slotted shingles locked by such fasteners. The crank arms of the fasteners afford sufficient leverage to turn their shanks in the roof boards under the expanding and

contracting movements of the shingles, without tearing the under-turned corners or distorting their slots.

In addition to this advantage, the fasteners can be produced at small cost and they permit ready locking of the shingles to the roof.

I claim as my invention:

1. The combination with a roof, of a shingle fastener comprising a driving shank, an arm extending laterally from the shank, a substantially T-shaped head carried by the arm, and a flexible shingle having a slotted

underturned corner interlocking with said fastener, the shingle slot being disposed at 15 an angle to the cross-bar of said T-head.

2. The combination with a roof, of a shingle fastener comprising a driving shank, an arm extending laterally from the shank, a cross-head at the free end of said arm and 20 a flexible shingle having a slotted underturned corner interlocking with said fastener, the cross-head of said fastener extending at an angle to said shank and to the slot in the shingle.

FELIX E. LIETZ.
